Fig. 4

Fig. 1 is a rear view of a combined toilet seat and end hinge posts showing my new design—the toilet bowl, seat and cover, and the upper part of the hinge being shown in dotted lines.

Fig. 2 is a side view of the left-hand toilet seat hinge post, the upper part of the hinge and portions of the toilet bowl, seat, and cover being shown in dotted lines.

Fig. 3 is a top view of the left-hand toilet seat hinge post.

Fig. 4 is a top view of the right-hand toilet seat hinge post.

The dominant features of my design reside in the parts shown in full lines.

I claim:

The ornamental design for a combined toilet seat and end hinge posts, substantially as shown and described.
